CLAIM

The ornamental design for a bag, as shown and described.

DESCRIPTION

FIG. 1 is a perspective view of a bag showing our design; FIG. 2 is front view of the design shown in FIG. 1; FIG. 3 is a rear view of the design shown in FIG. 1; FIG. 4 is a view of the design shown in FIG. 1 taken from a bottom left side of the bag at an upwards angle; FIG. 5 is a view of the design shown in FIG. 1 taken from a bottom right side of the bag at an upwards angle; and, FIG. 6 is a top view of the design shown in FIG. 1. The bottom of the bag forms no part of the claimed design.
